UNITED STATES PATENT OFFICE.

JOHN E. BELL, OF BROOKLYN, NEW YORK.

MARINE BOILER.

1,332,969.

Specification of Letters Patent. Patented Mar. 9, 1920.

Original application filed March 1, 1918, Serial No. 219,924. Divided and this application filed August 16, 1918. Serial No. 250,119.

To all whom it may concern:

Be it known that I, JOHN E. BELL, a citizen of the United States, residing at Brooklyn, county of Kings, and State of New York, have invented certain new and useful Improvements in Marine Boilers, of which the following is a full, clear, and exact description.

On March 1st, 1918, I filed in the United States Patent Office an application Serial No. 219,924, for a marine boiler in connection with which there is described a novel plan of boiler tube spacing, a system of baffling used in connection therewith, and a superheater arranged in certain novel and very effective relations with the boiler tubes. These features form the subject of the present application, which, therefore, is a division of that above referred to.

20 The present improvement pertains more particularly to the marine type of boiler, and in the specification which follows it is described in connection with a special form of such boiler devised by me, but its more 25 general applicability will be obvious from its nature and the objects accomplished by its peculiar disposition therein. These may best be comprehended from a specific description of the improvement, followed by 30 some observations of a general nature with regard to its functions and purpose.

In the drawings hereto annexed Figure 1 is a view in elevation of one side of a marine boiler, with parts of the casing therefor removed to exhibit the superheater and its relation to the structure.

Fig. 2 is a vertical cross-sectional view of the complete structure; and,

Fig. 3 is a similar cross-sectional view but 40 at right angles to the plane of Fig. 2.

For purposes of this case it is unnecessary to give more than a general description of the boiler as a whole, with which object in view reference may be had to Fig. 2. In 45 this figure the boiler is shown as furnished with a proper setting 1, the walls being built up in any suitable manner, and it is placed over a fire box 2, also of the usual character. The boiler proper is composed 50 of two continuous box-shaped headers 3 and 4, connected by straight tubes 5, inclined forward at an angle of 18° to the horizontal.

The steam and water drum 6 is connected by nipples 7 with the front header 3, and by 55 circulation tubes 8 with the rear header 4,

said last named tubes being in two rows, expanded into the drum above and below the center line respectively, and at the other end slightly bent so as to enter the rear header normally.

60

Opposite each boiler tube 5, and in the outer plates of the headers 3, are hand holes with slightly beveled sides, which are closed by conical plugs 9, and drawn by nuts 11, with a force that presses a soft metal seat or 65 gasket, with which these devices are usually furnished, to the shape of the opening and prevent further advance of the plugs.

The header plates 13 and 14 are connected by hollow stay bolts 12, and every other tube 70 5 is omitted from the second row and every other alternate row, as shown in Fig. 2, opposite the points occupied by the stay bolts. By this means each hollow stay bolt is at the center of a cluster of six boiler tubes, 75 and affords a very effective and convenient means for cleaning or dusting the tube, by the introduction of a steam or air lance 15, through said bolts.

The boiler tubes in the several rows are 80 spaced close together so that the gas velocity is high and little baffling is required. It will also be observed that the streams of hot gas passing between the tubes of the closely spaced rows expand and mix before they 85 impinge directly upon the tubes in the next succeeding row, owing to the position of the widely spaced tubes, while each closely spaced tube is almost directly in the path of the gases passing through the spaces between them and the widely spaced tubes below, and this is a matter of prime importance and adds greatly to the efficiency of 90 the boiler.

The boiler is supported by lugs 16 riveted 95 to the sides of the headers near the bottom, as shown in Fig. 1. These lugs rest in cradles 17 carried by the box-like casing 18, which surrounds the furnace. The boiler proper is surrounded by and inclosed in a 100 casing 19 which is secured to and supported by the headers so that the boiler and its casing form a single rigid structure. The casing is completed by the addition of two inches of suitable heat insulation 21, and 105 two inches of fire-brick 22 around the bank of tubes, while that portion of the casing which surrounds the furnace is lined with three inches of insulation 23 and nine inches of fire-brick 24.

110

At about the center of the bank of tubes 5 an open space is left to permit the installation of a superheater 25, the tubes of which run at right angles to those of the boiler 5 and are so placed as to leave empty spaces in the front and rear of the superheater. Under this superheater there is a baffle 26 (Fig. 3) and above it at front and back are two short baffles 27 and 28. These baffles, 10 together with a plate baffle 29, over the top of the bank of boiler tubes, with openings at front and rear as shown in Fig. 3, and two tile deflectors 30 immediately above the bottom row of boiler tubes, direct the hot gases 15 in a sinuous path through the empty spaces and through the bank of tubes, the direction of travel, in the main, being at right angles to all the tubes.

With the remaining structural details this 20 application is not concerned. It may be stated that the casing is provided with the usual and necessary doors for inspecting the superheater or for gaining access to the interior of the furnace; that any proper means 25 may be used for opening, closing or securing such doors; that provision may be made for burning either coal or oil under the boiler, and that the plan of pipe connections between the boiler tubes, drums and super- 30 heater may be such as is ordinarily employed or as necessity may require.

There is a peculiar and marked advantage 35 secured by the special system of baffling, which is of such a character that the gases are free to pass over all portions of the heating surfaces while at the same time the retarding effect on the draft is reduced to a minimum. The baffling used naturally leads to the location of the superheater in the position shown. It will however be observed 40 that on either side of this superheater is a space constituting a secondary combustion chamber in which the gases have a chance to mix before passing over the superheater tubes. This feature is of great importance 45 in a marine boiler where the volume of the furnace is limited. As carbon monoxide gas, at higher rates of driving, enters the tube bank, further combustion is prevented unless the gas can stream into a chamber such 50 as is provided for in this design in both sides of the superheater. In the absence of secondary combustion of this sort, flaming occurs in the uptake and the efficiency of the 55 boiler is reduced.

Furthermore, these open spaces establish a uniform temperature in the gases so that they contact with the superheater tubes with a steep temperature gradient. The gases 60 enter the superheater from two sides and at right angles to the tubes, so that when the surface of the tubes is composed of Foster rings, or corrugated, it will be thoroughly and effectively swept by such gases.

65 The peculiar spacing of the boiler tubes

shown results in a better distribution of the gases over and under the baffles. The gas flowing out of a wide space and through the narrow spaces between tubes will tend to have a higher velocity at one point than at another. Consequently, from the ordinary considerations of hydro-dynamics the gas pressure must be greatest at the points of highest velocity, and there will therefore be a flow of gas along the tubes in the wider 70 spaces toward points of low pressure which would result in equalizing the velocities through the narrow spaces.

This lateral flow with the system of baffling shown, will distribute the gas over and 80 under the baffles so that all portions of the boiler surface are more equally swept by the gases, and in the main the flow is transverse to the tubes through the narrow spaces. The arrangement also permits me to maintain 85 the baffle plates, especially if they be in contact with the closely spaced tubes at a temperature that will protect them from burning.

Having now described my invention what 90 I claim is:—

1. In a boiler of the kind described, the combination with a bank of tubes separated at an intermediate point in said bank to form a space, of a superheater located in 95 said space and so that secondary combustion chambers or spaces will be left at the forward and rear ends of the superheater and baffling to direct the flow of gases over the tubes of the boiler, through said combustion 100 chambers and the tubes of the superheater.

2. In a boiler of the kind described, the combination with a bank of tubes, divided into two groups with a space between, of a superheater with its tubes running at right 105 angles to the boiler tubes, supported in said space in such manner as to leave combustion chambers or spaces at the forward and rear sides of the same, and baffling to direct the flow of gases through said combustion chambers and over the tubes of the boiler and the 110 superheater transversely.

3. In a boiler of the kind described, the combination with a bank of tubes, divided into two groups with a space between them, 115 of a superheater located centrally in said space so as to leave empty spaces at its front and rear, a baffle plate under the superheater, a corresponding baffle above the same and over the bank of tubes, and end 120 baffles above and below the superheater, for causing the gases to flow in a sinuous path over the tubes and through the empty spaces.

4. In a boiler, the combination with a 125 bank of tubes expanded at their ends into continuous headers, and divided into two groups with a space between, of a superheater located centrally in said space with empty spaces at its front and rear, a baffle 130

- plate directly under the superheater, a corresponding baffle plate above the same and over the bank of tubes, short baffles between the boiler tubes immediately above the 5 empty spaces and above the lowermost row of boiler tubes, for causing the hot gases to follow a sinuous path through the empty spaces and through and over the tubes of the boiler and superheater.
- 10 5. In a boiler of the kind described, the combination with a bank of boiler tubes, the ends of which are expanded into continuous headers, and divided into two groups with a space between, of a superheater located

centrally in said space, with empty spaces 15 in front and rear, the tubes of said superheater running at right angles to the boiler tubes, a baffle plate under the superheater, and end baffles among the boiler tubes below and above the superheater space, whereby 20 the hot gases are directed over a sinuous path, through the empty spaces and through and over the tubes of the boiler and the superheater.

In testimony whereof I hereunto affix my 25 signature.

JOHN E. BELL.
